Oscar Guett.

UNITED STATES PATENT OFFICE.

FRANK WEKWERT, OF METZ, MICHIGAN.

WEAPON.

1,259,943.

Specification of Letters Patent. Patented Mar. 19, 1918.

Application filed August 22, 1917. Serial No. 187,728.

To all whom it may concern:

Be it known that I, FRANK WEKWERT, a citizen of the United States, resident of Metz, county of Presque Isle, and State of Michigan, have invented certain new and useful Improvements in Weapons, of which the following is a specification.

This invention relates to improvements in small arms, and has as its special object the provision of means whereby a revolver of the ordinary type may be combined with a sword, saber or the like in such manner that either may be used independently of the other or together without in any way interfering in the proper use of either.

A further object is to provide means which may be applied to existing revolvers, the application involving merely the removal and re-insertion of screws adapted to hold the parts together.

These and other like objects are attained by the novel construction and combination of parts hereafter described and shown in the accompanying drawing, forming a material part of this disclosure, and in which,

Figure 1 is a side elevational view showing the articles combined in accordance with the invention.

Fig. 2 is an enlarged side elevational view of a revolver and a fractional portion of a sword, connected therewith and

Fig. 3 is a top plan view of the sword hilt as adapted for engagement.

In the drawing a conventional type of revolver is represented, comprising a barrel 10, cartridge chamber 11, lock parts 12, and frame 15, the latter being provided with a guard 16 as is usual.

In the type shown in Fig. 2 the frame 15 is preferably of uniform thickness, and has attached to it a detachable handle 17, normally held in operative position by screws passing through the openings 18, while the blade 20 has a hilt 21, provided with a guard 22.

Formed through the sword hilt 21, is an open longitudinal slot 23, through which the trigger guard 16 of the revolver may extend, in such manner that the trigger 13 of the revolver may be operated with entire readiness.

A front extension 25 of the handle 21 has formed in it a recess 26, in which the handle 17 of the revolver may be received when the blade is engaged with the revolver, the handle acting as a distance piece between the barrel 10 and the hilt extension 25, it being held therein by means of the spring 27, secured at the front end of the extension, by a screw 28 or other like fastening means.

Also formed with the hilt 21 are pairs of lugs 30 and 31, suited to receive the engaging screws 32 which pass through the flat frame 15 on the revolver, thereby affording a rigid fastening means for the handle 17.

As the lugs 30 and 21 inclose the side of the revolver frame, lateral movement is prevented and longitudinal motion likewise, by the inserted screws 32, and it will be obvious that the handle 17, in the position shown in Fig. 2, also serves to engage the blade rigidly with the revolver, and in such manner that each is maintained in proper alignment thereby.

In operation, when it is desired to use the revolver as a small arm for firing purposes, it will be seen that the projectile issuing therefrom is fired above the back of the blade 20, the entire operation of discharging the revolver taking place without interfering or being interfered with by the attachment, and it will be equally obvious that the blade 20 is so secured that the revolver acts as a portion of the hilt by which it is manipulated and without interfering with the use of the blade.

Having thus described my invention, what I claim as new and desire to secure by Letters Patent, is—

1. The combination with a revolver having a flat frame, a trigger guard and a removable handle normally engaged therewith, of a sword blade, a hilt therefor, raised lugs on said hilt adapted to engage upon opposite sides of said revolver frame, and an opening through said sword handle receptive of the trigger guard of said revolver.

2. In a weapon, the combination with a revolver having a flat frame and an extending trigger guard, of a handle detachably

engaged with said frame, a sword blade, a hilt therefor, an opening formed through said hilt receptive of said trigger guard, lugs extending above said sword hilt, means 5 for engaging said lugs upon opposite sides of said revolver frame, and means for holding said revolver handle rigidly engaged be-

tween the barrel of said revolver and the hilt of said sword, whereby the parts are held in rigid engagement.

In testimony whereof I have affixed my signature.

10

FRANK WEKWERT.
